UNITED STATES PATENT OFFICE.

GEORGE EDWARD SLEEMAN, OF TORONTO, ONTARIO, CANADA.

DESIGN FOR A STATUETTE OR DOLL.

Application filed December 28, 1921. Serial No. 525,487. Term of patent 3½ years.

To all whom it may concern:

Be it known that I, GEORGE EDWARD SLEEMAN, a subject of the King of England, residing at Toronto, in the Province of Ontario, Canada, have invented a new, original, and ornamental Design for a Statuette or Doll, of which the following is a specification, reference being had to the accompanying drawing, forming part thereof.

In the drawing:—

The figure, is a perspective view of the statuette or doll.

I claim:—

The ornamental design for a statuette or doll, as shown.

GEORGE EDWARD SLEEMAN.
